INC., OF ROCHESTER, NEW YORK, A CORPORATION OF NEW YORK

EMERGENCY LOCK

Application filed October 6, 1931. Serial No. 567,224.

This invention relates to emergency locks of the kind used for emergency exit doors in theaters, schools and other places where people congregate and there is danger of fire or panic. The principal object of this invention is the provision of a lock of this kind which is simple and inexpensive to make and which efficiently locks a door from without but is readily released at any time by an outward push from within.

Another object of the invention is the provision of a lock of this type which is reversible, that is, a lock which is readily applicable to a door swinging either to the right or the left.

To these and other ends, the invention resides in certain arrangements and combinations of parts as will fully appear from the following description taken in conjunction with the accompanying drawings forming a part of this specification.

In the drawings:

Fig. 1 is a front elevation of a lock constructed according to one embodiment of the invention, the cover of the casing being removed to expose the interior and the handle being broken away to conserve space;

Fig. 2 is a horizontal section of the same taken substantially on line 2-2 of Fig. 1 and looking in the direction of the arrow at said line;

Fig. 3 is a fragmentary detail view showing relative positions of certain bolt actuating parts when the bolt is withdrawn;

Fig. 4 is a similar view but also showing the manually controlled means for holding the bolt withdrawn;

Fig. 5 is a sectional detail on the line 5-5, Fig. 1;

Figs. 6 and 7 show in face views and in reverse positions the lock mounted upon a door, the door being broken away and indicated in broken lines;

Fig. 8 is a plan of the lock as mounted in Fig. 6;

Fig. 9 is a side view of the same;

Fig. 10 is a sectional view on the line 10-10, Fig. 1, and

Figs. 11 and 12 show in detail cooperating

interlocking faces of the operating lever and the driving member.

In the drawings, similar reference numerals refer to similar parts throughout the several views.

The numeral 1 represents a locking bolt mounted for oscillating movement on a stud 2 having bearings in spaced lugs 3 upstanding from the bottom wall 4 of an open-faced casing, the wall 6 of which is cut away between the lugs 3 to permit movement of the bolt. This bolt 1 is provided with a pocket 7 which receives the head member 8 forming a connection between the bolt and an actuating rod 9, the head 8 being pivotally connected to the bolt by means of a stud 10 carried by the bolt and arranged across the pocket 7 parallel with the stud 2.

Oscillation of the bolt is effected by reciprocating movement of the rod 9 which lies substantially parallel with the sides of the casing and is guided in the slotted end of a lug 11 projecting from the wall 4, and the rod is provided with a cross-head 12 on its free end. A spring 13 is coiled about the rod and engages the fixed lug 11 at one end and the head member 8 at its other end and serves to resiliently project the bolt.

A stud 14 projects from the wall 4 of the casing on which is pivoted a bolt actuating member 15. A circular portion 16 of this actuating member 15 projects forwardly and has its center cut away to clear the rod 9 and to form radial lugs 17, one on each side of the rod normally engaging the head 12 adjacent its opposite ends. The rod actuating member 15 is also formed with a spur gear segment 18 which meshes with teeth on one side of a rack 19 slidably mounted in the casing and provided with teeth on an adjacent side engaged by a driving member 20.

The driving member 20 has a star-shaped opening 22 engaged by a star wheel 23 journaled in the casing, and also engaged in a star-shaped opening in an arm 24 whereby the arm is operatively connected with the driving member. The star wheel is detachably secured in the casing so that it may be released and removed from the driving member and its angular position, with respect to

the driving member, reversed, as indicated in Figs. 6 and 7, which permits the lock being placed at either the left or right side of a door.

It is preferable to have an operating handle extend substantially the full width of the door and, to this end, the outer end of the arm 24 has a reduced lateral extension 27 adapted to be received in an end of a tubular handle bar 28, the opposite end of which is similarly supported upon an arm 29 mounted to turn coaxially with the arm 24 in a bearing 30 projecting outwardly from a plate 31 secured to the door 26, lateral movement of the handle to engage or disengage the arm 24 and the driving member 20 causing the arm 29 to engage or disengage the bearing member 30.

The casing 5 is provided with opposing recesses at opposite ends of the rack 19. In one of these recesses is a block 34 removably secured to the bottom wall thereof by means of a screw, and in the other recess is a suitable resilient coiled spring 36, the block acting as a stop for the rack by engagement with a shouldered portion 37 thereon, and the spring engaging between a similar shouldered portion on the opposite end of the rack and the end wall of the recess in which it lies. The block 34 and spring 36 are interchangeable, and the direction of operative movement of the driving member 20 against the spring is determined by the arrangement of these two interchangeable members, in either event rotary movement of the driving member causing through the intermeshing racks and gear segments rotary movement of the member 15, which in turn, through one or other of the lugs 17 acting against the cross-head 12, effects rearward movement of the rod 9 and withdraws the bolt 1. On release of the operating handle, it and the members 20, 19 and 15 are returned to their normal positions by the spring 36, while the spring 13 throws the rod 9 forward to project the bolt 1, the lugs 17, when both are engaged by the cross-head 12, acting as stops to limit forward movement of the bolt.

Any suitable means may be provided for holding the bolt withdrawn. In this instance, a sleeve 38 is mounted to turn on a stud 39 on the wall of the casing and carries an arm 40 extending therefrom and adapted to engage the cross-head 12 and prevent forward movement of the rod. A leaf spring 41 anchored between the studs 42 and 43 has its free end bearing against flats on the sleeve 38 to yieldingly hold the sleeve with its arm 40 in either operative or inoperative position. The arm 40 is turned by means of a suitable key inserted in a socket provided therefor in the reduced end of the sleeve 38 projecting through the cover plate 45 of the casing. This cover plate is held in place by screws 46 threadedly arranged in alined bosses on the casing and cover, and the casing 5 is secured to a door 26 by suitable fastening de-

vices such as screws, engaging through openings 49 provided therefor in the wall 4 adjacent its top and bottom edges.

The lock is placed on the inside of a door and at the left, as in Fig. 6, or at the right as in Fig. 7, accordingly as the door is hinged at the right or the left side. If placed as in Fig. 6, the positions of the operating lever, spring 36 and stop block 34 are as shown in Figs. 1, 2 and 10, but should the lock be inverted and placed as in Fig. 7, the lever, including parts 28 and 29, is reversed so as to swing and occupy the same position relatively to the lock as in Fig. 9, and the spring 36 and block 34 are interchanged. In either location of the lock the handle has the same relative position to the door and the same outward movement for withdrawing the bolt. This outward movement of the handle causes a rotary movement of the member 15 through its rack and gear connection with the driving member 20, and such member 15 by one or other of the lugs 17 thereon, according to the right or left hand location of the lock, draws the rod 9 rearwardly and the bolt 1 to inoperative position, the springs 36 and 13 hereinbefore mentioned returning the parts to normal positions with the bolt projected when the handle is released. The bolt is projected independently of the return of the operating parts 15, 20 and 28 but not until the handle has been released to permit return of such parts, and if desired, the bolt is held withdrawn by means of the arm 40.

It will be understood that the bolt 1 by its surface 50 engaging the keeper in the door frame moves inwardly when the door is being closed, and that when the door is closed the bolt, by action of the spring 13, is projected with the surface 51 thereof engaging the keeper to hold the door against being opened until the bolt is withdrawn by means of the operating handle.

Although only one embodiment of the invention is shown and described herein, it will be understood that this application is intended to cover such changes or modifications as come within the spirit of the invention or scope of the following claims.

What I claim is:

1. In an emergency lock, the combination with a casing having a bottom wall comprising a support, of a pivoted bolt arranged to project through an opening in said casing, a rod slidably mounted on said support and pivotally connected with the bolt, resilient means on said rod for normally projecting the bolt, an operating member rotatably mounted on said support and operatively connected with said rod for withdrawing the bolt when turned in either direction, manually operated means rotatably mounted on said support for actuating said rotary member, a stop also rotatably mounted on said support and manually operable to and from

operative engagement with said rod to hold the bolt retracted against the tension of said resilient means, and separate resilient means for returning the rotary member and its
5 operating means to normal position while the bolt is held in withdrawn position.

2. In an emergency lock, the combination of a casing, a bolt pivoted therein, resilient means for projecting the bolt, a bolt retracting member comprising a gear segment, a rack slidably mounted in said casing and operatively connected with said gear segment, a manually operated member comprising a gear segment for operating said
10 rack, a spring engaging one end of said rack to resiliently retain it in normal position, and a stop in the path of the other end of said rack for limiting its movement under the action of said spring, said spring and stop
15 being interchangeable when the lock is reversed.

In witness whereof, I have hereunto signed my name.

FRANK J. BISHOP.
